[57] CLAIM

The ornamental design for a paper clip driver and applicator, as shown and described.

DESCRIPTION

FIG. 1 is a top plan view of a paper clip driver and applicator showing my new design;

FIG. 2 is a front elevational view;

FIG. 3 is a bottom plan view thereof;

FIG. 4 is a left side elevational view; and

FIG. 5 is a right side elevational view thereof.

The rear view is the mirror image of the front view.

FIG. 1

FIG. 2

FIG. 3

FIG. 4
